ABSTRACT OF THE DISCLOSURE

An improved apparatus for etching plates includes an enclosure for holding an etching solution and a spray assembly for spraying the etching solution on a plate located at an etching station within the enclosure. A plate handling and supporting assembly is provided for moving the plate between the etching station and an inspection station located in front of the enclosure. The plate handling means is adapted to rotate the plate while it is in an upended condition to facilitate inspection of the plate.

The present invention relates to the art of etching and more particularly to a method of and apparatus for etching a plate.

The present invention is particularly useful in the production of die plates to be used in cutting and creasing as in the formation of paperboard carton blanks. A complete disclosure of die plates of this type and the manner in which they are used to form a paper carton blank can be found in the patent to Downie No. 3,142,233, issued July 28, 1964.

The patent also discloses in considerable detail the manner in which the plates are prepared for etching. Briefly, the plate preparation involves the application of a coating which is etch resistant to the areas of the plate which are not to be etched. As the etchant contacts the plate surface it etches the uncoated areas of the plate to relieve the latter.

It has been discovered that in etching plates on which close pattern tolerances must be maintained, such as the die plate patterns disclosed in the previously identified patent to Downie, the etchant must be applied in uniform strength and quantity to all areas of the plate surface. To achieve this desired application of etchant, the present invention provides a plurality of spray tubes movable through the cabinet in a substantially linear path and delivers the etchant to the plate surface in the form of a spray in the course of their movement along the path. This moving spray application, due to the continuous mixing of the etchant as it is circulated through the system, maintains the strength of the etchant spray substantially uniform. To insure that the spray is uniformly applied to all areas of the plate surface, the plate is mounted for rotation about an axis extending substantially normal to the path of tube movement so that periodically, such as after a pass or passes of the spray, the plate can be rotated about this axis so that succeeding passes of the spray move across the plate in different paths. For example, in the case of etching a rectangularly shaped plate, the plate may be located successively in four positions, with each position being oriented 90° relative to the preceding and succeeding positions so that all edges of the plate are exposed to the leading edge of the spray as it is moved thereacross, consequently insuring uniform spray application to all portions of the emerging pattern.

One problem which arises in connection with etching plates is that of inspecting the plate without removing

2

it from the plate holder of the etching apparatus. The plates are often of large size and it is difficult for the workman to inspect the entire plate if it is maintained in the same orientation as during the etching process and when it is moved out of the etching area for inspection purposes, particularly when such orientation is horizontal. If the plate is in or shifted to a vertical position for inspection, the upper portion of the plate may be too high to allow convenient inspection by the workmen, particularly when it is recognized that the inspection is a microscopic type inspection.

Accordingly an important object of the present invention is to provide a new and improved apparatus for etching plates in which the plate may be readily and conveniently inspected without removing the plate from the support for holding it in etching position.

Another object of the present invention is the provision of a new and improved method of etching a plate by making a plurality of passes with a spray of etching fluid across the surface of the plate and angularly rotating the plate between passes.

Another object of the present invention is the provision of a new and improved apparatus for etching a plate wherein a rectangularly moving spray of etching fluid is directed onto a plate which is mounted for rotation about an axis extending substantially normal to the path of movement of the spray.

Another object of the present invention is the provision of new and improved etching apparatus in which a plate to be etched is supported in a substantially horizontal position in an enclosure to expose the plate to a spray of etching fluid and in a position inclined to the horizontal as it is withdrawn from the enclosure to receive a water spray which is directed onto the surface of the inclined plate to remove any etching fluid remaining on the plate and drain the fluid into the enclosure prior to emerging therefrom.

A further object of the present invention is the provision of a new and improved etching apparatus in which a plate, which is etched in a generally horizontal position, can be moved outside of the etching area, rotated about a generally horizontal axis to position the plate in an upstanding position for inspection purposes with the plate being rotated about an axis generally perpendicular to the plate while in the upstanding position.

A further object of the present invention is the provision of a new and improved means for producing a spray of etching fluid in an enclosure and which comprises a plurality of hollow tubes having discharge openings therein and which are bodily movable to produce a moving spray of etching fluid.

Further objects and advantages of the present invention will be apparent from the following detailed description of the preferred embodiment thereof made with reference to the accompanying drawings forming a part of the present specification for all subject matter disclosed therein and in which:

FIG. 1 is a perspective view of the apparatus embodying the present invention;

FIG. 2 is a sectional view of the apparatus embodying the present invention taken substantially along line 2—2 of FIG. 1;

FIG. 3 is a sectional view of the apparatus embodying the present invention taken substantially along line 3—3 of FIG. 2;

FIG. 4 is a sectional view showing the tube truck taken substantially along line 4—4 of FIG. 3;

FIG. 5 is a sectional view taken substantially along line 5—5 of FIG. 4;

FIG. 6 is a sectional view of a portion of the tube truck taken substantially along line 6—6 of FIG. 5;

FIG. 7 is a partial side elevation in section of the apparatus embodying the present invention illustrating the plate handling means disposed within the cabinet;

FIG. 8 is a sectional view of the portion of the plate handling means taken substantially along line 8-8 of FIG. 7;

FIG. 9 is a schematic view of the plate handling means illustrating the plate supported in the etching position;

FIG. 10 is a schematic view of the plate handling means illustrating the plate supported in the plate withdrawal position; and

FIG. 11 is a schematic view of the plate handling means illustrating the plate supported in an inspection position.

Referring to the drawings which disclose a preferred embodiment of the invention, the apparatus includes an enclosure in the form of a cabinet 10 within which a plate A is to be etched. The cabinet 10 comprises a tank 12 and a removable cover 14 mounted on the top of the tank 12. The cabinet is preferably constructed from stainless steel and has an opening disposed along a front or forward side thereof which is closed by a hinged door means 16. The tank 12 has an inclined bottom wall 18 which slopes downward to a fluid reservoir 20 formed in the lower left-hand portion of the cabinet as viewed in FIG. 1.

The plate handling means for supporting and handling the plate A during the etching operation is indicated generally by the numeral 22. The plate handling means is slidably mounted for movement between a position in which the plate A is forwardly or in front of the cabinet 10 at an inspection station (see FIGS. 1 and 3) and an etching station at which the plate is within the cabinet (see FIG. 7).

The plate handling means comprises a frame means 24, a base member 26 rotatably supported on frame 24, and a plate holder 28 rotatably supported on base member 26 which is in turn supported on a frame 24 for rotation about a horizontal axis. The frame 24 is movable into and out of the enclosure to move the plate A into and out of etching position and comprises two spaced parallel members 30 interconnected at one end by an angle 32. The frame members 30 are slidably mounted in a pair of movable slides 34 which in turn are slidably supported in telescoping relationship in fixed slide sections 36 secured to inside walls of the cabinet 10 and provides for sliding movement of the frame 24 relative to the cabinet from a position within the cabinet to a position outside and in front or forwardly of the cabinet and vice versa. Mounted on the ends of frame members 30 opposite angle 32 are a pair of trunnions 38 and 40 which extend normal to the frame members 30, and which support the base member 26 for rotation about an axis. The frame member 30 has a semicircular shaped plate 42 fixed secured thereto and which has, in the preferred embodiment, two angularly spaced notches 44 and 46 in the periphery thereof which are used to lock the base member 26 in different angular positions.

Base member 26 which supports the plate holder 28 comprises a substantially rectangular shaped body member 48 which has bushing members 50 and 52 fixedly projecting from respective sides thereof and which rotatably engage the trunnions 38 and 40 respectively and are held in assembled relationship with the trunnions by means of caps 54 which are secured in any suitable manner to the trunnions. Base member 26 is thus free to rotate relative to the frame 24 about trunnions 38 and 40. The base member 26 has a handle 56 for rotating base 26 relative to frame 24. The handle 56 comprises two elongated members 58 and 60 arranged in spaced parallel relationship to one another and connected at one of their ends to the body member 48 and are interconnected at their opposite ends by a gripping member 62. The base member 26 is secured in a selected position relative to frame member 24 by means of a first latch

means 64 secured to one end of base member 26 and arranged to cooperate with the notches in plate 42 to effect a coupling therewith. The first latch means comprises a bolt slidably mounted in a guide. The bolt is normally biased by a spring to an extended latching position in engagement with the periphery of plate 42. As base member 26 is rotated, the bolt rides on the periphery of plate 42 and enters one of the notches 44, 46 when the base member reaches one of its desired positions of adjustment. The bolt is moved out of the notches by means of a cable connected at one end to the bolt and slidably mounted in a cable housing 66 which extends from the latch means 64 to handle member 60. A cable actuator 68 is attached to the other end of the cable and is effective upon operation to unlatch base 26 from frame 24 to permit the base to be moved to another position.

The plate holder member 28 is rotatably mounted on base member 26 by means of a sleeve 70 centrally arranged on body member 48 to fixedly support a trunnion 72 by means of a cap plate 74. A bushing 90 projects outward from one side of a plate support means 86 and is rotatably mounted on trunnion 72. The bushing is held in assembled relationship theron by means of cap 92. A plurality of angularly disposed ribs 91 strengthen the mounting of bushing 90.

The plate support means 86 comprises a plate which is substantially square in plan in the preferred embodiment and has a reinforcing rib 88 on the side opposite the side to which the plate A is adapted to be attached.

The plate A to be etched is secured to the plate support means 86 by suitable locking dogs 100 which are adjustably arranged on the plate support means 86 so as to be capable of securing plates of different size and shapes thereto. The plate holder means 22 is rotatable relative to the base member 26 about an axis passing through trunnion 72 and perpendicular to the plate A. Means are provided to fix plate holder 28 relative to base 26 in one of four positions and comprises two latch mechanisms 94 (FIG. 8) secured to member 48 adjacent bushing 90 and having bolts 96 biased by means of a spring into engagement with bushing 90 carried by the plate holder means 28. Four recesses 98 are disposed around the periphery of bushing 90 at 90° intervals and into which bolts 96 are adapted to extend when in aligned relationship therewith and function when in this relationship to fix the plate support means 86 relative to base 26. To change the relative position of these members, the plate support means 86 is rotated to force the bolts 96 against the bias of the springs out of seating engagement with their associated recesses 98. Rotation of plate support means continues until bolts 96 enter the adjacent previously unengaged recesses 98. Thus the plate can be fixed relative to base 26 in any one of four positions. Of course, if desirable, more or less than four positions of adjustment could be provided by adding or subtracting recesses 98 in the bushing 90.

The described plate handling means supports plate A for rotation about two axes which are normal to one another and for movement into and out of cabinet 10 wherein the etching operation is accomplished. To insure proper positioning of the plate A in cabinet 10 a latch mechanism 76 (FIG. 3) is provided and is secured to body member 48 of base member 26 at the side opposite the side on which the handle 56 is mounted. This latch mechanism is similar to latching mechanism 64 and is operated by a rod 78 extending through member 48 and along the handle member 58 and has a rod actuator 80 connected to the end thereof. The bolt of the latching means is arranged to enter a key slot 82 in an angle member 84 in cabinet 10 when the plate A is properly arranged in etching position in the cabinet 10. This position is illustrated in FIG. 7. After the plate has been properly secured in a position to be etched in cabinet 10, means are provided to move a spray of etching fluid across the plate surface and com-

prises a plurality of spray tubes 102 mounted at their respective ends on trucks 104 having wheels 106 disposed to run in tracks or guideways 108 supported on opposite side walls of the cabinet 10. A drive means 110 is operatively connected to the trucks and adapted to move the spray tubes back and forth across the cabinet beneath the plate A supported by the plate handling means 22. The plate handling means and the spray tubes are arranged in the preferred embodiment to move in directions normal to one another. The spray tubes 102 have a series of openings 112 in the upper portion thereof and through which the etching fluid is adapted to be dispensed in the form of a spray. The etching fluid is delivered to the spray tubes 102 by pump means 114 (FIG. 1) driven by a suitable power means 116. The pump means includes suitable piping 118 for connecting the pump with the reservoir 20 and with the trucks 104. The piping 118 has suitable valves and flow indicator and a T-section 120 disposed in cabinet 10 (FIG. 3). A flexible hose 122 is connected to each end of the T-section 120 and extends therefrom to the trucks 104. The etching fluid in reservoir 20 is removed by pump 114 and circulated through piping 118, hoses 122, trucks 104, suitable passageways in the trucks into the spray tube 102 where it is dispersed through openings 112 as a spray. The etching fluid after being dispersed by tubes 102 accumulates in reservoir 20 and is recirculated to the tubes. Periodically the etching fluid loses its strength and has to be replaced. By manipulation of certain valves the etching fluid can be directed into a drain and a cleaning liquid, such as water, is circulated through the tubes 102 and the piping. Water can also be delivered to the tank through pipe 119 to rinse the surfaces of the tank 12.

Disposed above the tubes 102 is a baffle 124 defining an opening having generally the same configuration as, but smaller than, the plate support means 86. The baffle 124 and plate support means 86 cooperate to form a barrier across the tank to prevent the spray of fluid from entering into the section of the tank above plate A as the spray tubes traverse the cabinet. The precise configuration of the opening defined by baffle 124 preferably conforms to the plan configuration of plate 86. The configuration in the preferred embodiment is square with cut out corners similar to a Swiss-cross. The cut out corner configuration facilitates rotation of the plate support means relative to the cabinet when the former is disposed in etching position in the latter.

The trucks 104 supporting the spray tubes 102 for movement in cabinet 10 and the tubes are preferably constructed from acid resistant material, such as Teflon, and each truck comprises a lower body section 126 of unitary construction and four upper body sections 128 which are removably secured to lower section 126 by a plurality of threaded fasteners 130. Each upper section 128 is capped by a metal plate 132, preferably of stainless steel, and the lower section 126 has a single plate 134 which also is preferably made from stainless steel. The threaded fasteners 130 extend through openings in the upper plate 132, the associated upper section 128, lower section 126 and plate 134. To facilitate mounting the innermost two fasteners 130 of plates 132, a metal plate 184 (FIGS. 5 and 6) is welded to the upper side of plate 134 and extends across opening 174 and has the head of the bolts 130 welded or otherwise secured to the upper edge thereof and the threaded ends of the bolts extend through the Teflon body sections 126, 128 and upper plate 132 and threaded receives the associated nuts 186. This arrangement, of course, is necessitated due to the connection of collar 176 to plate 134 at the area where these bolts or fasteners 130 would normally extend through plate 134.

Disposed along the back side of lower section 126 (FIG. 5) is a plate 136 which is secured at its lower end by any suitable means, such as by welding, to the bottom plate 134 which projects rearwardly beyond the lower Teflon section 126. A pair of axles 138 are secured to backing plate 136 and onto which the truck wheels 140

are rotatably mounted. The rollers 140 also are preferably constructed from Teflon. A suitable guideway, or track, 142 is welded, or otherwise secured, to the sides of cabinet 10 and along which the truck wheels 140 are adapted to run.

The tubes are secured to the trucks by means of an inner pipe or conduit 143 which extends through the Teflon truck body between the upper sections 128 and lower section 126. The inner pipe 143 is secured at one end in abutting relationship to back plate 136 by a threaded fastener 144 and the other end is secured in concentric relationship to an end of the tube 102 by a suitable bushing 146 mounted in the end of tube 102. The end of tube 102 is arranged to extend partially into the upper and lower Teflon sections between plates 128 and plate 134, as is clearly shown in FIG. 5 of the drawings. The tube mounting arrangement is such as to permit quick removal thereof from the trucks by removing the associated plate 132 and upper body section 128 of each truck.

The drive means 110 for the trucks 104 comprises a suitable motor means 148 which is mounted on a shelf 150 secured to the exterior of cabinet 10. A shaft 152 extends the width of cabinet 10 and is rotatably supported at the respective sides thereof by suitable bearing means 154. Disposed on each end of drive shaft 152 are sprockets 156 which are keyed or otherwise fixedly secured to rotate with the shaft. Disposed at the opposite end of cabinet 10 is an idler shaft 158 having a pair of sprockets 160 mounted on respective ends thereof in alignment with sprockets 156. Drive shaft 152 extends through one side of cabinet 10 and has mounted thereon a sprocket 162 which is driven from motor sprocket 164 through a suitable drive belt 166 such as a link chain belt. A pair of link chains 166 are disposed about sprockets 156 and 160 and the respective ends of each chain are connected to plate 168 depending from bottom plates 134 of the trucks. A pair of chain guide plates 170 project upwardly and are secured to guideways 142 by means of suitable fasteners 172 and functions to support the upper runs of the chains. Upon actuation of motor means 148, power is transmitted therefrom through sprockets 164, 162 and 156 to chains 166 to propel the trucks 104 along guideways 142 to move the tubes in a substantially linear path.

Means are provided for establishing fluid communication through each of the trucks from the flexible hoses 122 to the spray tubes 102 and comprises an opening 174 in bottom plate 134 and a circular collar 176 depending from plate 134 from within opening 174 and onto which the end of hose 122 is connected. The upper and lower Teflon body sections 126 and 128 have formed therein suitable passageways for providing fluid communication between collar 176 and tubes 102 and comprises a main fluid passageway 178 in the lower Teflon section 126, and a series of annular passageways 180 formed in the upper and lower Teflon sections 126 and 128 to provide communication between each inner pipe 143 and the main passageway 178. Each inner pipe 143 has an opening 182 in the upper portion thereof disposed in the annular passageway 180 so as to provide fluid communication therebetween. As fluid is pumped through hoses 122 it flows under pressure through collar 176, main passageway 178, annular passageways 180, opening 182 in the inner pipe 143 and into each end of tubes 102 where it is dispersed therefrom through openings 112. The etchant flow through the trucks is shown by the arrows in FIG. 6.

The operation of the etching apparatus will now be described. The machine is initially set in the position illustrated in FIG. 1 with the plate holder means 28 oriented substantially vertically which is the plate attaching and removal position. The plate holder means is fixed in this position while the plate A is attached to the plate support means 86 by the latch means 64 engaging notch 46 of plate 42. The plate is delivered to the machine by a suit-

able material handling means such as an overhead crane, conveyor, etc., and is locked in position by adjustment of locking dogs 100 with the side to be etched exposed. After the plate A has been secured to the plate holder means, the operator grasps cable actuator 68 and exerts a force thereon which disengages the bolt of the latch means 64 from notch 46 and thereafter the operator rotates the base 26 relative to frame 24 by handle means 56 until the plate assumes the position illustrated in FIG. 9. This position is characterized by the spring latch means being positioned slightly below notch 44 of plate 42 which is the position in which the plate is substantially horizontal. With the plate in this position, the operator pushes on member 62 which moves frame 24 along telescoping slides 34 and 36 to locate the plate within the cabinet 10 in the position illustrated in FIG. 7. To assure proper alignment of the plate handling means relative to the cabinet and also to maintain the plate A in the horizontal position while the etching is accomplished, the bolt of latch means 76 is aligned to extend into key slot 82 of the angle 84. With the plate in this position, the door 16 is closed. Suitable motor control means in control panel 188 mounted on cabinet 10 is actuated along with suitable pump control means which also is mounted in control panel 188 and function to deliver the etching fluid under pressure to the tubes 102 through pump 114, piping 118, T-joint 120, hoses 122, collars 176, main passageways 178 of the trucks 104 and through the annular passageways 180 into the openings 182 in the inner pipes 143 and out pipes 143 into tubes 102 where it is subsequently dispensed in the form of a spray through openings 112 in the top side of the tubes 102. After sufficient etching fluid has been pumped to the tubes 102 so that an even spray is dispensed therefrom, the drive means 110 for the trucks is actuated including motor 148, sprockets 164, 162, 156, 160 and chain 166 and which move the tubes 102 across the cabinet below the face of plate A and delivers to the plate a spray of etching fluid which corrodes the plate according to the established pattern thereon. As the tube trucks 104 complete their etching pass by reaching the opposite side of cabinet 10, one of the trucks engages the switch actuator of a suitable switch 190 which functions to shut off the drive means 110 and reverse the motor 148. Upon subsequent actuation of the drive means 110, the tubes will be moved in the opposite direction to the opposite side of the cabinet where they will be stopped by one of the trucks engaging a second limit switch 190 similar to the other limit switch but disposed at the opposite side of the cabinet. The switches referred to are limit switches wherein the switch is mounted on the exterior of the cabinet with only the switch actuator mechanism projecting into the cabinet in position to be engaged by the trucks at opposite ends of their path of travel. In order to insure even quality of etching on plate A, it is desirable to rotate plate A 90° between passes of the etching spray tubes 102. To accomplish this rotation, the operator opens door 16, grasps one end of plate support means 86 and rotates same 90° until latch means 96 drops into recesses 98 in the bushing 90 which secures the plate relative to the base 26 in the new position. Door 16 is then closed, whereupon the controls are again actuated to drive tube trucks 104 to make another etching pass at the plate. After each pass or after several passes, the plate is again rotated relative to base 26 heretofore described so as to present all sides of the pattern being formed on plate A to the etching spray. This minimizes the streaking effect and uneven chemical etching of the plate by the movable spray.

Periodically the operator will want to inspect the etching progress on plate A. To accomplish this, he open door 16 of cabinet 10, grasps rod actuator 80 and disengages latch means 76 from slot 82 in angle 84 and the base is rotated by handle 56 until the latch means 64 engages notch 44 on plate 42. This position of adjustment is illustrated schematically in FIG. 10 and is the position

of plate A during withdrawal thereof from cabinet 10. As noted in FIG. 10, this portion holds plate A at an inclined relationship relative to frame 24 and as the plate handling means is withdrawn from the cabinet a water spray is directed against the etched surface of plate A to wash any etchant remaining on the plate therefrom prior to emerging from the cabinet. The water spray is dispersed through a water spray tube 192 located at the entrance end of the opening in cabinet 10. The cabinet has an inclined plate 194 located adjacent tube 192 and which slopes into a collection trough 196. The water sprayed onto the etched surface of plate A drains off the plate face due to the inclined relationship of the plate and the water and etchant mixture flows down plate 194 into trough 196. Suitable drainage means such as a hose is connected to trough 196 to drain the mixture which accumulates in trough 196. After the plate A has been completely removed from cabinet 10 and is in front of the cabinet, base member 26 can be rotated by handle 56 to a convenient inspection position which could be the position illustrated in FIG. 1 wherein the latch 64 is in engagement with slot 46, or alternatively a third notch 198 could be provided in plate 42 so as to hold plate A in the inspection position illustrated in FIG. 11. This position permits manipulation of the plate to facilitate precise measurement of the depth of etch of the plate to determine the progress of the etching operation thereon. Of course, as mentioned previously, any number of notches might be provided in plate 42 to provide more fixed positions of adjustment of base member 26 relative to the frame 24.

A pair of vents 200 are provided in the cabinet 10 and are adapted to be connected to an exhaust system to vent the fumes and gases produced by the chemical etching operation.

While the preferred embodiment of the present invention has been described in considerable detail, it is hereby my intention to cover further constructions, modifications and arrangements which fall within the ability of those skilled in the art and within the scope and spirit of the present invention.

Having described our invention, what we claim is:

1. In an etching apparatus, an enclosure for holding an etching solution and having a front exterior wall at least partially defining an opening in said enclosure, plate handling means connected to said enclosure and adapted to support a plate to be etched, means mounting said plate handling means for moving said plate through said opening between an inspection station at which the plate is disposed exteriorly of said enclosure and forwardly of said front wall and an etching station at which the plate is disposed within said enclosure with the surface to be etched exposed for etching, and means for impinging the etching solution against said surface of the plate to thereby effect an etching of said surface, said plate handling means including means supporting the plate for rotation about a first axis and a second axis normal to said first axis with the plate in an upended condition with said surface facing away from said enclosure when said plate is at said inspection station, whereby the plate can be adjusted to facilitate inspection of said surface.

2. The apparatus defined in claim 1 including means supporting said plate for rotation about said first and second axes when at said etching station to facilitate manipulation thereof for etching.

3. The apparatus as defined in claim 2 including means for releasably securing said plate in a selected one of a plurality of positions of rotation about said axes when said plate is disposed at said inspection and etching stations.

4. The apparatus defined in claim 1 including means supporting said plate in a substantially horizontal position when at said etching station and means supporting said plate in a position inclined to the horizontal as the plate is moved from said etching to said inspection station.

5. The apparatus defined in claim 1 including means supporting said plate for rotation about one of said axes at said etching station.

6. In an etching apparatus, an enclosure for holding an etching solution and having an opening along one side thereof, plate handling means adapted to support a plate to be etched and arranged to move said plate through said opening between an inspection station at which the plate is exterior of said enclosure and an etching station at which the plate is disposed in said enclosure with the surface to be etched exposed for etching, and means for impinging the etching solution against said surface of the plate to thereby effect an etching of said surface, said plate handling means comprising a frame member slidably mounted on said enclosure and arranged to move through said opening, a base member mounted on said frame member for rotation relative thereto about a first axis, a plate holder member mounted on said base member for rotation relative thereto about a second axis normal to said first axis, means on said plate holder member to secure a plate thereto, first locking means associated with said base member in a selected effective to releasably lock the base member in a selected one of a plurality of positions relative to said frame member and second locking means associated with said base member and said plate holder member to secure the latter relative to the former in a selected one of a plurality of positions.

7. The apparatus described in claim 6 wherein said first locking means comprises an arcuate-shaped plate carried by said frame member and having a plurality of notches disposed about the periphery thereof, a latch mechanism on said base member and having a latch means biased into contact with the periphery of said arcuate plate and adapted to engage said notches to secure the base member relative to the frame member in a selected one of a plurality of positions, said latch mechanism further including means connected to said latch means and operable to move said latch means against its bias out of engagement with its associated notch to free said base member to rotate relative to said frame.

8. The apparatus as described in claim 6 wherein said second locking means comprises latch means on said base member and a plurality of mating recesses on said plate holder member and means for biasing said latch means into engagement with said recesses.

9. The apparatus defined in claim 1 wherein said means for impinging etching solution against the plate includes a plurality of tubes having discharge openings therein, means for delivering etching fluid to said tubes under pressure to be dispersed through said openings in the form of a spray, means mounting said tubes for movement in said enclosure and drive means for moving said tubes.

10. The apparatus as described in claim 6 wherein said means for impinging etching solution against the plate includes a plurality of tubes having discharge openings therein, trucks supporting the opposite ends of said tubes and movable along guideways supported by said enclosure, drive means operatively connected to said trucks and effective to move said trucks along said guideways, each of said trucks having fluid passageway means therein in communication with the associated tube ends,

and means for delivering said etching fluid under pressure to said passageway means and discharged through said openings in said tubes to establish said spray.

5 11. In an etching apparatus adapted to etch a pattern on a plate surface, an enclosure having a front wall, means for producing a spray of etching fluid in said enclosure, means mounting said spray producing means for movement in a linear path in said enclosure, drive means for moving said spray producing means along said path, and plate handling means adapted to support a plate at an etching station in said enclosure with the surface to be etched arranged to intercept said spray as said spray producing means is moved along said path by said drive means and to move said plate to an inspection station forwardly of said front wall, said plate handling means including means for supporting said plate for rotation at said etching station about an axis normal to said linear path of movement of said spray producing means whereat rotation of said plate about said axis presents different portions of the pattern being etched on said plate to said spray and for rotation at said inspection station about an axis extending generally along said path of movement whereat rotation of said plate about said last named axis facilities inspection of different portions of the pattern being etched on said plate.

20 12. In an etching apparatus, an enclosure having an opening therein, means for producing a spray of etching fluid in said enclosure, plate handling means connected to said enclosure and adapted to support a plate to be etched and arranged to move said plate through said opening between an inspection position in which the plate is disposed exteriorly of said enclosure and forwardly of the front wall of said enclosure to an etching position in which the plate is disposed within said enclosure with the surface to be etched arranged to intercept said spray, means supporting the plate on said plate handling means for rotation about an axis from a generally horizontal position to a position inclined relative to said horizontal position when in said etching position means for maintaining the plate in said horizontal position when in said etching position, means for maintaining the plate in said inclined position as it is moved from said etching position to said inspection position, and means effective to direct a water spray on the surface of the plate when in said inclined position whereby etching fluid remaining on the plate will be washed off prior to the plate reaching said inspection position.

25 13. The apparatus as defined in claim 12, including means supporting said plate for rotation about an axis normal to said first axis.

UNITED STATES PATENT OFFICE
CERTIFICATE OF CORRECTION

Patent No. 3,455,763 Dated July 15, 1969

Inventor(s) Albert J. Sarka & Louis P. Toth

It is certified that error appears in the above-identified patent and that said Letters Patent are hereby corrected as shown below:

In the claims, Column 9, line 22, after "base" insert -- and frame--, also in the same line change "member" to --members-- and delete the rest of the line.

In the claims, Column 10, line 35, delete the entire line 35.
